ATTORNEY.

INVENTOR.

UNITED STATES PATENT OFFICE.

BENJAMIN E. BOSLER, OF JOHNSTOWN, PENNSYLVANIA.

PUNCH.

1,040,497.

Specification of Letters Patent.

Patented Oct. 8, 1912.

Application filed June 22, 1909. Serial No. 503,591.

To all whom it may concern:

Be it known that I, BENJAMIN E. BOSLER, a citizen of the United States, residing in the city of Johnstown, in the county of Cambria and State of Pennsylvania, have invented certain new and useful Improvements in Punches; and I do hereby declare the following to be a full, clear, and exact description of the invention, such as will 10 enable others skilled in the art to which it appertains to make and use the same.

My invention relates to punches used in perforating metal and especially to those which form a flat surface around the hole to 15 provide a bearing for a bolt-head, nut, or washer.

This type of punch is adapted for use in the manufacture of splice-bars for railway-rails or for forming bolt-holes in any object 20 having a curved surface.

The object of my invention is to provide a punch in which the hole-forming part is removable from the part which forms the flat bearing surface around the hole, both 25 of which parts may be made separate from the punch-stock. This form of construction enables the same stock to be used for different punches and also obviates the necessity for replacing the entire punch whenever 30 there is a flaw in but one part.

Referring to the sheet of drawings accompanying this specification, in which like characters of reference indicate like parts throughout the views:—Figure 1 is a vertical transverse section through the lower part of a punching apparatus, showing my improved punch in position. This figure also shows the relative positions of the punch, die, splice-bar and clamp for holding the splice-bar, at the extreme end of a stroke of the punch. Fig. 2 is a vertical transverse section of a punch-stock, showing an oval punch in elevation and Fig. 3 is a bottom plan view of the same. Fig. 4 is a 45 vertical transverse section of a punch-stock, showing a circular punch in elevation and Fig. 5 is a bottom plan view of the same.

Referring now to the drawings in detail, 1 indicates the ram which is reciprocated by

suitable means not shown. The punch-holder 2 is adjustably mounted on the ram and secured as shown. The clamping-die 3 is secured to rods 4 which pass through and above the ram. These rods are used in operating the clamping-die, the mechanism 55 not being shown. The die 5 for the punch is inserted in the die-block 6 which is adjustably mounted on the bed 7. The upper end of my improved punch-stock 8 is tensioned so as to fit into a corresponding mortise on the punch-holder. The lower end of the stock is made smaller than the body part and is threaded to fit the cap forging member 9. The cap forging member and stock may be made of the same or of different 60 degrees of hardness as desired. The lower face of the cap forging member is made substantially flat and is used in forming a bearing surface around the holes made by the punch. The punch 10 abuts the lower 65 end of the punch-stock and is held in place by the cap forging member 9.

In punching oval holes in splice-bars it is desirable to have the long axis of the holes parallel to the axis of the bar. In order to 70 hold the punch in the proper position and prevent it from turning during use, I provide the tenon 11 on the punch and a corresponding mortise in the punch-holder as shown in Figs. 1, 2 and 3. This construction 75 may be dispensed with in the case of circular punches, the punch and stock then being of the form shown in Figs. 4 and 5.

Although I have shown and described my improvements in considerable detail, I do 80 not wish to be limited to the exact and specific details shown and described, but may use, such substitutions, modifications or equivalents thereof, as are embraced within the scope of my invention, or as pointed out 85 in the claim.

Having thus described my invention, what I claim and desire to secure by Letters Patent is:

In apparatus for punching splice-bars, a 90 pair of clamping dies shaped to conform to the rail-fit portions of said bars, means for holding the same firmly, a punch, a punch-

stock, and a swaging-cap having a flat end of larger diameter than said punch surrounding and clamping said punch rigidly to said stock, the punch being adapted to 5 make a hole in the splice-bar and the swaging-cap to indent and make a flat surface around the punched hole.

In testimony whereof I hereto affix my signature in the presence of two witnesses.

BENJAMIN E. BOSLER.

Witnesses:
